US0D1097328S

(12) **United States Design Patent** (10) **Patent No.:** **US D1,097,328 S**
(45) **Date of Patent:** **** Oct. 7, 2025**

(54) **ELECTRIC SHAVER**

(71) Applicant: **Shenzhen JoeYears Technology Co., Ltd.**, Shenzhen (CN)

(72) Inventor: **Zhihua Tang**, Guangdong (CN)

(73) Assignee: **Shenzhen JoeYears Technology Co., Ltd.**, Shenzhen (CN)

(**) Term: **15 Years**

(21) Appl. No.: **29/995,241**

(22) Filed: **Mar. 25, 2025**

(30) **Foreign Application Priority Data**

Dec. 16, 2024 (CN) 202430799094.8

(57) **CLAIM**

The ornamental design for an electric shaver, as shown and described.

DESCRIPTION

FIG. 1 is a first perspective view of an electric shaver showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the electric shaver that form no part of the claimed design.

1 Claim, 8 Drawing Sheets
